UNITED STATES PATENT OFFICE.

LEVANDER BROWN, JR., OF MONTREAL, QUEBEC, CANADA.

PAINTING MACHINE.

Application filed December 21, 1922. Serial No. 608,383.

To all whom it may concern:

Be it known that I, LEVANDER BROWN, JR., mechanical supervisor, of the city of Montreal, Province of Quebec, Dominion of Canada, have invented certain new and useful Improvements in Painting Machines; and I do hereby declare that the following is a full, clear, and exact description thereof.

My invention relates particularly to painting machines of the type in which boards, planks, scantlings, posts, studs and the like and other things requiring painting are passed through a receptacle or chamber containing the liquid paint and during the process the articles are dipped in the paint. There has been considerable waste of paint and time incident to these methods of painting and the paint has not been uniformly applied and my invention has for its object to overcome these disadvantages.

To this end my invention may be said broadly to consist in subjecting boards, planks, scantlings, and the like and in fact any article it may be desired to give a complete or partial coat of paint, to a fine spray of paint in a machine consisting of a tank for containing the liquid paint in its lower portion and a series of pipes having their lower ends submerged in the paint and their upper ends in the form of nozzles located comparatively close to the article to be painted as it is supported in the chamber within the tank above the body of liquid paint. Compressed air nozzles with proper pipe connections are supported preferably at right angles to the paint nozzles and with the paint nozzles so directed that the flow of compressed air across the mouth of the paint nozzles will spray the paint in atomized form over the article or a portion of it according to the angular positions of the atomizers. In the preferred embodiment of the invention the tank is mounted on a truck in the form of a four wheeled buggy, the tank being closed on all sides and the top while openings in its opposite ends are provided for the introduction of the boards, etc., at one end and their discharge at the opposite end. Paint atomizers are located in position to spray the top, sides and bottom of the boards, etc., as they pass through the tank. I have provided, as will be presently shown, a particular arrangement of piping to feed the atomizers. This arrangement of piping may be varied, and the pipes may be fixed or movable. The paint is agitated to prevent settling, preferably by compressed air. As a compression of air will be developed within the tank and consequently a tendency given to the atomized paint to flow outwardly through the feed and discharge openings for the boards, etc., an exhaust is provided which consists preferably of a duct in the form of a relatively large bore pipe communicating with the upper end of the atomizing chamber within the upper portion of the tank, such exhaust pipe standing above the tank and having a condenser or separator at its upper end by which the paint particles are separated from the air flowing therethrough to the atmosphere, the paint thus separated being returned to the tank. The exhaust is accelerated by a jet of compressed air direct into the duct and projecting in the direction of the condenser or separator. I also provide for the separation of the surplus paint in the atmosphere of the chamber above the sprays, this being effected by flat inclined surfaces upon which the paint is precipitated and which conduct the paint thus collected away from the articles being painted and return it to the body of paint in the bottom of the tank. The suction pipes by which the paint is drawn to the atomizers have strainers on their bottom ends to prevent thickened paint or foreign substances from obstructing the pipes.

One of the particular features of this invention is the condenser or separator by which particles of paint are separated from the air exhausted from the atomizing chamber. This condenser or separator is adapted to present inclined baffling faces to the atomized paint as it leaves the duct to reclaim the surplus paint, these faces coating in such a manner that the draft without being retarded is caused to follow a tortuous path as it leaves the duct and in doing so precipitating the paint particles on these faces. In the outward flow it passes through a perforated screen and is again deflected by other faces and made to return through the perforated screen in the reverse direction and is finally deflected upwardly and out of the condenser or separator. This causes further precipitation with each change of direction with the result that the minimum amount of paint passes to the atmosphere while the reclaimed paint is conducted back to the tank. Valves for regulating the supply of compressed air, and supports and guides for the articles when

they are passed through the machine and the mechanical feed also form features of my invention.

For full comprehension, however, of my invention reference must be had to the accompanying drawings in which similar reference characters indicate the same parts and wherein:

Figure 1 is a part plan and part horizontal sectional view of my improved paint machine, the section being taken on line 1—1 Figure 5;

Figure 2 is a longitudinal vertical sectional view taken on line 2—2 Figure 1;

Figure 3 is a rear elevation of the buggy;

Figure 4 is a detail elevation of the feed mechanism for introducing the articles to be painted;

Figure 5 is a transverse sectional view taken on line 5—5 Figure 2;

Figure 6 is a front elevation of the machine;

Figure 7 is a detail plan view of the paint separator for the exhaust duct;

Figure 8 is a side elevation of the machine illustrating particularly the arrangement for piping and system of valves for controlling the air supply, regulating the atomizers and controlling the agitator;

Figures 9 and 10 are side elevation and plan view respectively of one of the atomizers;

Figures 11 and 12 are detail illustrations of the nozzle common to all the atomizers;

Figures 13 and 14 are detail views of one of the strainers for the paint suction pipes;

Figure 15 is a detail perspective view of the interior of the separator and illustrating particularly the faces for deflecting the atomized paint and collecting the precipitated paint particles;

Figure 16 is a transverse vertical sectional view of the separator taken on line 16—16 Figure 17;

Figure 17 is a detail plan of the underside of the box with the bottom removed for the purpose of better illustration of the particular arrangement of the baffle devices; and

Figures 18, 19 and 20 are detail views of one of the baffling devices removed and shown in elevation from the center of the box, side elevation and inside plan view respectively.

In the preferred embodiment of my invention illustrated in the drawings the tank is represented as a wooden box-like structure having sides 20, 21, ends 22 and 23, a bottom 24 presenting forwardly extending center sill 124 and top 25, the sides being reinforced by bars 26. The rear and front ends of the box 22 and 23 respectively have openings 28 and 27 respectively for the entry of boards, etc. and egress thereof,

these openings being covered on the outside

by curtains 29, the tank apart from the openings 27 and 28 and the top, is hermetically sealed to hold a body of liquid paint and the atomized paint above the liquid body.

The top 25 is hinged to provide access to the interior of the tank.

The atomizers as indicated at 30, 31, 32, 33, 34 and 35 each consists of an oil or paint nozzle 36 and air nozzle 37 connected by an elbow 38 to project at right angles to each other. These nozzles and the complete atomizer formed thereby are shown in detail in Figures 1, 2, 5 and 9. The air nozzles of the atomizers are connected to a main compressed air supply pipe 46 by pipes 40, 41 and 42 through valve controlled branches 47, 48 and 49, the air connection

from any available source of compressed air is indicated at 43 and the end of this main pipe 46 has a blow-off cock 44. The oil or paint nozzles have feed pipes 45 each having strainers covering its lower end and consisting preferably of a brass wire screen

50 with perforated tin top and bottom ends 51 and 52 respectively. These strainers are illustrated in detail in Figures 13 and 14. The lower ends of these oil pipes are located a short distance above the bottom of the tank. An agitator located on the bottom of the tank consists of a jet frame

consisting of a feed pipe 55, a longitudinal horizontal pipe 56 coupled thereto and having four transverse branch pipes 57, these pipes 57 having perforations in their sides through which jets of compressed air are projected horizontally into the liquid paint body, the effect being that a state of ebullition is maintained in the paint body and the subsidence of the paint and consequent separation of the pigment from the oil vehicle is prevented. This agitator is connected by pipe 60 to a branch 61 controlled by a valve 62 and leading from the main air supply pipe 46. Universal joints connect all the nozzles in place and permit adjustment.

The exhaust duct consists of a stand pipe 70 of relatively large bore carrying the paint separator. It is connected by branches 71 to suction ducts 72 carried by the side 21 of the tank near the top thereof and communicating with the chamber in the tank above the body of paint. The lower end of this stand pipe has a reclaimed paint pipe

75 connected thereto and communicating at its lower end with a horizontal pipe 76 entering the tank above the paint body and communicating in turn with a pipe 77 extending downwardly in the paint body. This pipe 76, for convenience, is extended inwardly beyond pipe 77 to present a support 78 for the boards, etc. as they are fed through the machine. This will be presently further alluded to. The paint con-

130

denser or separator carried by the top of the stand pipe consists preferably of a rectangular box 80 the center of the bottom of which has a coupling 81 by which it is connected to the top of stand pipe 70. There is also a paint drainage pipe 82 connected by a pipe union to the bottom of the condenser box preferably at one corner and communicating at its lower end, by an elbow 83 with a T-coupling 84 by which communication is also effected between the pipes 75 and 76. The box preferably consists of galvanized iron and has its top edge inwardly bevelled to shed water as at 87 forming the edge of an opening 88 closed by a cover 89 having a counterweight in the form of a balanced nut 90 on a stem 91 so arranged and balanced that the pressure of the outward flowing air will raise the cover 20 and permit of the exhaust. The opening 85 in the bottom of the condensing box and communicating with the stand pipe 70 is surrounded by a rectangular enclosure 86 of perforated plate or wire netting extending 25 from the bottom to within a short distance of the mouth of the box, and the opening 85 has extending above it a series of baffling devices in the form of inclined vanes presented by angular imperforate plates 100. 30 These plates are cut to present when folded a rectangle triangle with their longest edges or bases 101 soldered or otherwise rigidly secured to the side of the perforated rectangular enclosure 86 thus presenting apices 35 102 making contact with the sides of the enclosure at a level located about one-third distance from the top of the enclosure while the apices of the right angles being located midway of the height of these devices disposes 40 the ridges 103 in planes of 45 degrees to the sides of the enclosure. The edges 104 of the several devices are soldered together. The structure thus produced is of star form in plan view and as it extends completely over 45 the mouth 85 of the uptake 70, the draft, induced in a manner to be presently alluded to, will meet the point 105 and be divided and deflected upwardly and outwardly as will be presently shown. 50 The draft is induced by a jet of compressed air directed up the pipe 70 by a nozzle 110 on the end of a pipe 112 controlled by a valve 113 through which the acceleration of the draft up the pipe 70 is regulated. The air pipe 112 extends 55 through the side of the tank and through a plug 114 in a T-coupling 115 coupled to one end of the pipe 78, the other end of which is coupled to a T-coupling 116 connecting this pipe 78 and the pipe 76 and 77 together, the pipe 112 continuing through the coupling 115, pipe 78, coupling 116, pipe 76, T-coupling 84 and upwardly in the pipe 70. The vertical opening in coupling 60 115 is plugged as at 117.

The T-coupling 115 is employed for convenience in construction, this fitting being ordinarily carried in stock and readily available while as it conforms to the coupling 116 it lends uniformity to the design 70 of the machines and at the same time the flanges 119 and 120 serve as guides for the boards, etc. supported by the pipe 78 while being fed through the machine.

In order to prevent dripping of paint 75 from the roof of the atomizing chamber onto the boards, etc. being passed through the machine a galvanized iron plate bent to present surfaces 125 inclined downwardly throughout the full length of the chamber 80 is attached to the underside of the cover of the machine, the side of this plate adjacent to the cover hinges is extended and inclined downwardly as at 126 to deflect the paint drippings into the tank when the cover is 85 raised.

To facilitate the handling of the unpainted boards, etc. before they pass through the machine a platform 130 is extended forwardly from the tank with its surface in a 90 horizontal plane of the sill of the entering and discharge openings 28 and 27. This platform is presented by the top 131 of a tool box 132, the top being covered by a sheet of galvanized iron and the sides of 95 the box being extended as at 133 to support the platform while a hinged door 134 permits of access to the tool box. Guides are secured on the platform to direct the boards. This tool box is supported on the 100 side sills. The boards, etc. are fed mechanically into the machine by a pair of rubber rollers 150 and 151, the roller 150 being driven by shaft 152 which in turn is driven by an air turbine 152^a. The latter is supplied with air through a pipe 152^b which is connected to pipe 61 as indicated in Figure 8. A pair of gears 153 and 154 carried by this shaft and a shaft 155 of roller 151 transmit rotation from shaft 152 to shaft 155. 110 The surface of the supporting roller 150 is supported slightly above the inclined sill of the intake opening 28 of the tank by a frame 161 of U-form, the ends of the legs 115 of which are diminished as at 162 and screw-threaded and passed upwardly through the flange 159 of an angle iron bracket 160 secured by bolts 161 to the receiving end of the tank and suspended by adjusting nuts 163. The supporting frame is held in 120 proper position by a bracket 164 slotted as at 165 to which it is adjustably bolted as at 166 to the tank. The shaft 155 is rotatably suspended in bearings 156 and the lower ends of suspension rods 157 are adjustably 125 supported by nuts 158 resting on the horizontal flange 159. This feed roll 151 is variable as to its feed position to accommodate different thicknesses of boards, etc. and in order to allow of this the suspension rods 130

157 are provided with encircling springs 170 supported by nuts 171 and bearing between them and the underside of flange 159. These springs 170 give pressure to the upper feed 5 roll. A clean-out pipe 200 provided with a valve is connected through the bottom of the tank.

The machine is made mobile by being mounted on four wheels 201, the front pair 10 being on a pivoted truck provided with a handle 202 for the purpose.

It may be found desirable to couple my painting machine to a planing machine and feed the boards directly from the latter to 15 the former and it is to be distinctly understood that the same comes within the scope of the present invention.

Operation.

- 20 The tank is first charged preferably to the depth indicated in Figure 5 and the nozzles of the atomizers being first adjusted to direct sprays of atomized paint against the surfaces of the boards, etc. as they pass 25 through the box. The adjustment of the nozzles of each atomizer relatively to each other and in relation to the thicknesses and widths of the boards, etc. is effected by turning the nozzle pipe arms at the various joints 30 which enables the nozzles to be directed where desired. The boards are fed into the tank through opening 28 by the feed rollers to which they are fed by hand. As they are projected through the machine they are supported by the platform, the bottom roller of 35 the feed device and on pipe 78 and guided by the flanges 119 and 120 and issue through opening 27 from which they are removed and disposed for drying. As the boards, 40 etc. pass through the machine the spray from atomizers 30 and 31 completely coat the top surface while the atomizers 32 and 33 coat the side surface and the atomizers 34 and 35 the bottom surfaces. The valve 45 113 is first opened which causes a draft from the tank to be induced into exhaust duct 70, the agitator valve 62 is then opened thus stirring up the paint in the tank. The valves of the atomizers are then opened and 50 the machine commences operation. As the boards pass through the machine the intake and outlet openings 28 and 27 are closed by the curtains 29, the suction of the exhaust duct creating an inward motion of the atmosphere through these openings thus preventing the atomized paint from finding its way into the room or area where the machine is being operated, the atomizing chamber 55 within the tank above the liquid paint being charged with the paint vapor, and the paint content of the atmosphere of this chamber being high and the atomizers projecting sprays directly onto the surface of the boards, etc. However fast the latter are 60 fed through the chamber they immediately 65

become completely coated with paint. While this operation is going on the draft of exhaust duct 70, with its accelerator 110, causes a gentle movement of the atmosphere of the chamber upwardly through the duct to the paint separator 80. In this separator the current of paint laden air, as shown in Figure 5, comes first in contact with the under sides of the inclined faces of the star shaped deflecting surfaces by which the flow 70 is deflected outwardly in all directions and through the perforated plate 86 and is again deflected and turned back by the interior of the flat sides of box 80 and again passes through the perforated plate 86 to be a third time deflected by the upper inclined faces of the star and finally by the inclined flange 87 surrounding the outlet mouth of the box. These deflectors of the paint laden air 75 causes the paint to be precipitated on the various surfaces by which it is deflected and through which it passes and it finds its way from the star, both sides of the inclined plates of which shed the precipitated paint, 80 from the perforated sides of the enclosure 86 and the interior of the box 80 to the reclaimed paint pipe 82 and thence by pipe 76, fitting 116, and pipe 77 to the body of paint in the tank. The air thus liberated is 85 discharged through opening 89. The paint precipitated on the surface above the things being painted will drip beyond the side edges thereof and thus prevent spotting.

Although I have described my invention 90 with relation to the coating of boards, etc. with paint it is equally applicable to the treatment of any articles with a substance 95 without departing from the spirit of my invention.

What I claim is as follows:

1. In a portable tank for the treatment of articles with a substance, said tank having an entrance in one wall and an exit in an opposite wall for permitting the passage of the articles in a straight line through the box, means for atomizing the substance within the chamber, said means consisting of a plurality of relatively fixed atomizers, means for subjecting the articles to the atomized substance within the chamber and means for exhausting the atmosphere from the chamber.

2. In a portable tank for the treatment of articles with a substance, the interior of the tank constituting an open chamber containing the substance, means for atomizing the substance within the chamber, means for subjecting the articles to the atomized substance within the chamber, means for exhausting the atmosphere from the chamber and means for reclaiming the paint from the atmosphere exhausted from the chamber.

3. In a portable tank for the treatment of articles with a substance, the interior of the box constituting an open chamber contain-

- ing the substance, means for atomizing the substance within the chamber, means for subjecting the articles to the atomized substance within the chamber and means for deflecting dripping of the substance within the chamber from the articles. 5 for coupling the air and liquid nozzles in pairs, means for positioning the air nozzles relatively to the liquid nozzles to form atomizers, means for supporting the said atomizers relatively to the articles to be treated. 70
4. In a chamber for treating articles with a substance, means for atomizing the substance within the chamber consisting of a tank for containing the liquid substance, an agitator, an atomizer within the chamber with its suction pipe dipping into the liquid and its air pipe projecting through one wall of the chamber, said chamber having aligned entrance and exit openings in oppositely disposed walls, and means for feeding the articles to be treated through the openings. 10 75
5. In an apparatus of the type described a receptacle for containing a liquid substance for the treatment of articles, means for atomizing the substance within the receptacle, means for exhausting the atmosphere from the receptacle, means for reclaiming the paint from the atmosphere exhausted from the receptacle consisting of a vertical exhaust duct having at its top a device for deflecting the air current flowing from the duct, and means for collecting the substance precipitated by the deflection of the air currents. 20 80
6. In a chamber for the treatment of articles with a substance, means for atomizing the substance within the chamber, means for subjecting the articles to the atomized substance within the chamber, means for exhausting the atmosphere from the chamber and means for reclaiming the paint from the atmosphere exhausted from the chamber consisting of a vertical exhaust duct having at its top a device for deflecting the air current flowing from the duct and means for reclaiming the substance precipitated by the deflection of the air currents and returning it to the chamber. 25 85
7. In a chamber for the treatment of articles with a substance, a pressure fluid supply, means for atomizing the substance within the chamber, said means being connected to the pressure fluid-supply and means for subjecting the articles to the atomized substance within the chamber consisting of means operatively connected to the pressure fluid supply and actuated by the pressure fluid for mechanically feeding the articles through the chamber. 30 90
8. A portable machine for treating articles consisting of a tank the interior of which constitutes a unitary chamber for containing in its lower portion a liquid treatment substance, atomizing means located within the chamber, said means consisting of a series of pipes with their lower ends dipping into the liquid and having nozzles at their upper ends, a series of compressed air pipes with nozzles at their ends, means for coupling the air and liquid nozzles in pairs, means for positioning the air nozzles relatively to the liquid nozzles to form atomizers, means for supporting the said atomizers relatively to the articles to be treated, means for agitating the liquid substance consisting of a perforated hollow device. 35 95
9. A portable machine for treating articles consisting of a tank for containing in its lower portion a liquid treatment substance and presenting a chamber in its upper portion, a series of pipes with their lower ends dipping into the liquid, and having nozzles at their upper ends, a series of compressed air pipes with nozzles at their ends, means for coupling the air and liquid nozzles in pairs, means for adjustably positioning the air nozzles relatively to the liquid nozzles to form atomizers, and means for supporting the said atomizers relatively to the articles to be treated. 40 100
10. A portable machine for treating articles consisting of a tank for containing in its lower portion a liquid treatment substance and presenting a chamber in its upper portion, a series of pipes with their lower ends dipping into the liquid and having nozzles at their upper ends, a series of compressed air pipes with nozzles at their ends, means for coupling the air and liquid nozzles in pairs, means for positioning the air nozzles relatively to the liquid nozzles to form atomizers, means for adjustably supporting the said atomizers relatively to the articles to be treated. 45 105
11. A portable machine for treating articles consisting of a tank for containing in its lower portion a liquid treatment substance and presenting a chamber in its upper portion, a series of pipes with their lower ends dipping into the liquid and having nozzles at their upper ends, series of compressed air pipes with nozzles at their ends, means for coupling the air and liquid nozzles in pairs, means for positioning the air nozzles relatively to the liquid nozzles to form atomizers, means for supporting the said atomizers relatively to the articles to be treated and means for agitating the liquid substance. 50 110
12. A machine for treating articles consisting of a tank for containing in its lower portion a liquid treatment substance and presenting a chamber in its upper portion, a series of pipes with their lower ends dipping into the liquid and having nozzles at their upper ends, a series of compressed air pipes with nozzles at their ends, means for coupling the air and liquid nozzles in pairs, means for positioning the air nozzles relatively to the liquid nozzles to form atomizers, means for supporting the said atomizers relatively to the articles to be treated, means for agitating the liquid substance consisting of a perforated hollow device. 55 115
- 60 120
- 65 125
- 70 130

13. A portable machine for treating articles consisting of a tank for containing in its lower portion a liquid treatment substance and presenting a chamber in its upper portion, a series of pipes with their lower ends dipping into the liquid and having nozzles at their upper ends, series of compressed air pipes with nozzles at their ends, means for coupling the air and liquid nozzles in pairs, means for positioning the air nozzles relatively to the liquid nozzles to form atomizers, means for supporting the said atomizers relatively to the articles to be treated, means for agitating the liquid substance. a perpendicular exhaust duct communicating with the upper portion of the chamber, means for accelerating the exhaust draft in the duct and means for reclaiming the substance carried through the duct by the exhaust draft.

14. A machine for treating articles consisting of a tank for containing in its lower portion a liquid treatment substance and presenting a chamber in its upper portion, a series of pipes with their lower ends dipping into the liquid and having nozzles at their upper ends, a series of compressed air pipes with nozzles at their ends, means for coupling the air and liquid nozzles in pairs, means for positioning the air nozzles relatively to the liquid nozzles to form atomizers, means for supporting the said atomizers relatively to the articles to be treated, means for agitating the liquid substance, a perpendicular exhaust duct communicating with the upper portion of the chamber, means for accelerating the exhaust draft in the duct, means for reclaiming the substance carried through the duct by the exhaust draft and means for returning the substance to the tank.

15. In a portable apparatus of the type described a liquid containing chamber having an exhaust duct, means for atomizing the liquid in the chamber, and means for accelerating the exhaust draft in the duct, the said accelerating means consisting of a compressed air pipe extending upwardly into the duct for projecting a jet or series of jets of compressed air.

16. In an apparatus of the type described, a tank, atomizing means, a perpendicular exhaust duct communicating therewith, means for reclaiming the substance carried through the duct by the exhaust draft, and means for returning the substance to the tank, said means consisting of a box containing a separator communicating with the exhaust duct, a pipe effecting communication between the bottom of the box and the tank, and deflecting devices located within the box.

17. In an apparatus of the type described a tank, atomizing means, a perpendicular exhaust duct communicating with the tank,

means for accelerating the exhaust draft in the duct, means for reclaiming the substance carried through the duct by the exhaust draft and means for returning the substance to the tank consisting of a box containing a separator mounted upon the top of and communicating with the exhaust duct, and a pipe communicating with the bottom of the said box and extending downwardly and across the bottom of the duct in the tank.

18. In an apparatus of the type described, a tank containing a liquid substance, means for atomizing the substance within the tank, means for presenting articles to the action of atomizing means, and means for preventing the liquid from dripping from the roof of the chamber onto said articles, said last mentioned means consisting of a device secured to the underside of the roof of the tank and presenting surfaces inclined downwardly from the centre of the chamber to points beyond the vertical peripheral planes of the articles.

19. In a machine of the type described, a tank adapted to contain a liquid atomizing means, an exhaust duct communicating with the interior of the tank, means for accelerating the exhaust draft in the duct, and means for reclaiming the liquid carried through the duct by the exhaust draft, said last mentioned means consisting of a hollow receptacle having an inlet with which said exhaust duct communicates, said receptacle having an exhaust opening and a balanced cover for normally closing said opening, a separator located within said receptacle over said inlet and consisting of a perforated enclosure and a series of inclined baffling devices positioned within said enclosure and adapted to divide the incoming draft and direct same upwardly and outwardly and means for conducting the reclaimed liquid to the tank.

20. In a machine of the type described a tank adapted to contain a liquid atomizing means, a vertically disposed exhaust duct communicating at its lower end with the interior of the tank at a point above the level of the liquid therein, means for accelerating the exhaust draft in the duct and means for reclaiming the liquid carried through the duct by the exhaust draft, said last mentioned means consisting of a hollow metal box of rectangular form mounted upon the upper end of the exhaust duct and having an inlet communicating therewith, the top of said box having an exhaust opening and a balanced cover for normally closing said opening, a separator located within said box over said inlet and consisting of a perforated rectangular enclosure and a series of baffling devices positioned within said enclosure over the inlet and forming a member of inverted pyramidal

form with star shaped base, the apex of the pyramid located in the center of the inlet opening whereby the incoming draft is divided and deflected upwardly and outwardly through the perforated enclosure in the box and means for conducting the reclaimed liquid to the tank.

21. In a portable machine of the type described a tank for containing a liquid substance, means for atomizing the substance within the tank, means for feeding articles to be coated with the substance through said tank, pressure fluid actuating means for driving said feeding means, and a pressure fluid supply duct communicating with said atomizing means and the pressure fluid actuated means.
22. In a machine of the type described a tank adapted to contain a liquid substance, means for atomizing the substance within the tank, means for feeding articles to be coated with the substance within the tank, said means consisting of a pair of parallel feed rollers, means for rotating the rollers consisting of a pressure fluid driven motor operatively connected thereto, and a pressure fluid supply duct communicating with the motor and with the atomizing means.
23. In a machine of the type described an exhaust duct, a receptacle having an inlet opening communicating with the exhaust duct, a baffle extending across the said inlet and causing the exhaust flow to spread laterally into contact with the adjacent walls of the receptacle, and perforated division walls surrounding the baffle and intersecting the path of the exhaust flow after it is spread.
24. In a portable machine of the type described a tank mounted upon a truck in the form of a four-wheeled buggy said tank consisting of a wooden box-like structure of rectangular form the interior of which constitutes a chamber adapted to contain a fluid substance, the front and rear walls having openings therein one of said openings being for the purpose of inserting the article to be treated and the other for withdrawing the article after being treated, flexible means for closing the openings, atomizing means located within said chamber, and a platform mounted upon the buggy adjacent the inserting opening and adapted to receive and guide the articles about to pass through the tank.

In testimony whereof I have signed my name to this specification.

LEVANDER BROWN, JR.
